(57) **CLAIM**

I claim the ornamental design for a bottle, as shown and described.

DESCRIPTION

FIG. 1 is an upper perspective view of the bottle showing my design.

FIG. 2 is a side elevational view thereof;

FIG. 3 is a back elevation view thereof;

FIG. 4 is a side view thereof;

FIG. 5 is a front elevational view thereof;

FIG. 6 is a top view thereof; and,

FIG. 7 is a bottom view thereof.

The broken line showing in FIG. 7 is for illustrative purposes only and forms no part of the claimed design.
